UNITED STATES PATENT OFFICE.

GRAFTON E. LUCE, OF CHICAGO, ILLINOIS.

BRICK CLAMPER.

Application filed March 7, 1927. Serial No. 173,590.

This invention relates to a brick clamping construction adapted to clamp a brick resting upon a support, the clamping construction and the brick support being relatively 5 movable, and generally the brick support being a movable conveyer such as an "off-bearing" belt, the brick or article to be clamped being of plastic clay and the like which cannot be subjected to excessive clamping 10 pressures, such excessive pressures resulting in deformation of the plastic article.

The chief feature of the invention consists in the construction of a fluid operable article clamping device of the general 15 character hereinbefore indicated.

The full nature of the invention will be understood from the accompanying drawings and the following description and 20 claims.

In the drawings, Fig. 1 is a side elevational view of a support, a clamping construction supported thereby, an article to be clamped such as a brick and a support for the latter. Fig. 2 is an end elevation of the 25 same showing the parts in non-clamping relation. Fig. 3 is a view similar to Fig. 2 showing the parts in the clamping position.

In the drawings 10 indicates a channel member which is straddled by a pair of U-shaped straps 11, the central portions of said straps supporting therebeneath a transverse member 12 by means of the rivets 13 or equivalent constructions. The upper and free ends of the U-shaped straps 11 project 30 above the channel 10 and carry pins 14 that support rollers 15 which bear and roll upon the upper side of the channel. It is to be understood that an angle, T or I-beam or equivalent construction may be substituted 35 for the channel 10 without departing from the invention.

Suitably secured to the transverse member 12 is an angular plate having a parallel portion 16 and the depending portion 17, 40 said plate being secured to said support as by the rivets 18. Positioned parallel to the depending plate 17 and in spaced relation therewith is another plate 19, which plate is substantially diamond-shaped in outline as 45 shown clearly in Fig. 1. The ends of the diamond shaped plate portions 19 and 17 are suitably connected together by means of the screw bolts and nuts 20 and 20^A and in the framework thus formed, there is 50 mounted a fluid operable member such as the coil 21. Positioned at each side of the

parallel plate members 17 and 19 is an armature plate 22. Said armature plate 22 extends upwardly beyond the coil 21 as shown clearly in Fig. 1 and is provided with a pair 60 of apertures 23 which receive a pair of projecting pins 24 supported by the base or support 12. The plate 22 is further extended and is provided with a pair of openings 25. These openings 25 are adapted to 65 receive the angularly positioned ends 26 of a spring 27 interposed between the upwardly extending ends of the plates 22 and positioned between the U-shaped straps 11. The spring 27 is normally in tension and tends 70 to draw the upper ends of the plates 22 together, thereby causing the lower ends of the plates 22 to become further separated, the fulcrum for this tilting movement being furnished by the pins 24. When the 75 coil 21 is energized, the same attracts the armature plates 22 to the metallic core 28 and thus the lower ends of the parallel plates 22 are caused to move inwardly towards each other in opposition to the spring 80 27, the tilting movement taking place upon the aforesaid fulcrum provided by the pins 24.

Each of the armature plates 22 includes 85 an angular extension 31, and depending from said angular extension 31 is a spring or resilient strip or finger 32, which is provided with an angularly extending end 33. Said spring strip 32 is suitably secured to the depending extensions 31 of the plate 22 90 as by means of the rivets 34. The end of the spring member 33 suitably supports as by means of the rivets 35, a bearing member 36 for clamping engagement upon a brick 37 or the like, which article to be clamped may 95 or may not be in plastic state, but is supported in a suitable manner as by means of an offbearing belt 38.

It will be readily apparent from an examination of Fig. 1 that the clamping construction may move longitudinally along the supporting member 10 and thus move parallel to the belt either with the belt or in opposition thereto. Likewise the rates of movement of the clamping construction may be such that relative movement occurs therebetween, or the arrangement may be such that the movable element may be the offbearing belt; whereby when the clamping construction engages a brick or the like thereon, the entire clamping construction will be carried 105 in a direction parallel to the offbearing belt 110.

and by the same through the engagement of the brick thereon. The terminology "electrical operable means" is to be construed as including means operating in the same manner as that specifically disclosed herein and operable by electrical pressure, or equivalent means which can be similarly operated by fluid pressure including liquid pressure and pneumatic pressure, or by the absence of pressure such as a vacuum device.

The invention claimed is:

1. In a clamping construction, the combination of a support, a clamping construction movably supported thereby, a support therefor positioned beneath the first mentioned support, said clamping construction including a pair of horizontally fulcrumed opposed clamping plates, electrical operable means for causing said plates to move together to engage and clamp an article, and yielding means associated with said clamping plates for normally maintaining said plates in non-clamping relation, said electrical operable means actuating said plates in opposition to said yielding means.
2. In a clamping construction, the combination of a plurality of U-shaped supporting bracket members, a transverse support supported thereby, a pair of clamping plates fulcrumed upon said support, and electrical operable power means suspended from and supported by said support between said clamping plates.
3. In a clamping construction, the combination of a plurality of U-shaped supporting bracket members, a transverse support sup-

ported thereby, a pair of clamping plates fulcrumed upon said support, electrical operable power means suspended from and supported by said support between said clamping plates, and a spring positioned between a pair of said U-shaped supporting brackets above said transverse support and connected to said clamping plates for normally maintaining said plates in non-clamping position.

4. In a clamping construction, the combination of a supporting base, a pair of clamping members fulcrumed thereon and supported thereby, electrical operable power means supported by said base and between said clamping members for moving the same towards each other, and article engaging spring extensions connected to said clamping plates and movable therewith and flexed thereby into clamping engagement.

5. In a clamping construction, the combination of a supporting base, a pair of clamping members fulcrumed thereon and supported thereby, electrical operable power means supported by said base and between said clamping members for moving the same towards each other, article engaging spring extensions connected to said clamping plates and movable therewith and flexed thereby into clamping engagement, and yielding means associated with said clamping plates for normally maintaining said clamping plates in non-clamping position.

In witness whereof, I have hereunto affixed my signature.

GRAFTON E. LUCE.
